UNITED STATES PATENT OFFICE.

WILLIAM H. VOSS, OF DAVENPORT, IOWA.

WASHING-MACHINE AND GEAR.

1,108,531.

Specification of Letters Patent. Patented Aug. 25, 1914.

Application filed March 2, 1912. Serial No. 681,228.

To all whom it may concern:

Be it known that I, WILLIAM H. Voss, a citizen of the United States, residing at Davenport, in the county of Scott and State 5 of Iowa, have invented new and useful Improvements in Washing-Machines and Gears, of which the following is a specification.

It is the object of the present invention to provide an improved washing machine 10 equipped with gearing and other mechanisms so arranged that the agitator is located at the bottom of the tub with its pins extending upward, connections being provided for driving the agitator through the 15 bottom of the tub, instead of through the lid of the washer.

It is a further object of the present invention to provide a metal bottom for the tub and to arrange the agitator in such a 20 way that a water seal is provided above the driving connections where they enter the tub.

It is a further object to provide special 25 driving connections, whereby either hand power or engine power may be applied to actuate the agitator and whereby, if desired, a wringer attached to the washing machine may be driven either forward or backward and may be instantly stopped, started or 30 reversed, at the will of the operator.

For a better understanding of the invention, reference may be had to the following description, taken in conjunction with the 35 accompanying drawings, wherein—

Figure 1 is an elevation partly in section showing the complete washing machine. Fig. 2 is a plan view showing the platform under the tub, and Fig. 3 is a sectional elevation through the agitator.

In the construction shown in the drawings, the washing machine comprises a tub 1 mounted on four legs 2 in the usual manner. The bottom of this tub, instead of being made of wood, consists of a steel plate 3 45 of circular outline fitted at its edge into an annular groove in the staves of the tub.

The agitator or dolly instead of being supported from the lid of the washer, as in common practice, is supported from the 50 steel bottom 3 as shown in Fig. 3. The agitator or dolly comprises a wooden block 4 carrying three pins 5, made of wood and long enough to reach almost to the lid 6 of the tub. This agitator is supported on a 55 galvanized cast iron sleeve 7 closed at its top 8 and provided at its lower edge with an

outstanding flange 9, on which the wooden block 4 is carried and to which it is secured by bolts 10. The upper end 8 of the cast iron sleeve has a square socket which slips 60 over the upper end of a square shaft 11, serviceable as the driving shaft for moving the agitator intermittently in opposite directions.

A brass bushing 12 is secured near the upper end of the square shaft 11 by a pin 13 and this bushing rests on the top of a tubular support 14 and serves as a bearing for the agitator when it rotates. The lower end of the tubular support 14 passes through the 70 steel bottom 3 of the tub and is screwed into a flanged cast iron plate 15 suitably secured to the bottom of the tub with a water tight connection. The tube 14 serves not only as a bearing or support for the agitator, but it also prevents water from running through the bottom of the tub. It will be apparent that the dasher can be lifted out of the tub at any time when emptying the tub of clothes, without in any 75 way disturbing the parts of the mechanism. The agitator is supported far enough above the bottom 3 to prevent any rubbing or friction on the bottom.

The square shaft 11 carries a second brass 80 bushing 16 which fits into the lower end of the tubular support 14 and acts as a bearing. The lower end of this bushing is shaped to form a bearing for a gear 17. A pin 18 supports gear 17 and this in turn 85 keeps bushing 16 from dropping out of place. A sliding clutch 19 is carried on the lower end of the squared shaft and can be slipped up into driving engagement with the notched flange on the gear 17 and so establish driving connection between that gear and the square shaft 11. A rack 20 meshes with gear 17 and can be driven forward and backward to rotate the agitator first in one direction and then in the other.

The means for driving the rack 20 comprises a lever 21 pivotally mounted at 22 to a suitable platform carried on braces between the legs of the tub. This lever is moved backward and forward by means of 105 a link 23 pivotally connected to the upper end of lever 21 and also pivotally connected to the side lever 24 or actuating arm whereby the machine may be operated by hand power applied to the handle 25. A forward 110 and backward movement of the handle 25 moves rack 20 forward and backward and

when the sliding clutch 19 is in its raised or driving position, a connection is established to the square shaft 11 and the agitator of the machine rotates first in one direction and 5 then in the other direction, thereby swinging the clothes and the water against the sides of the tub. The means for shifting clutch 19 comprises a hand lever 26 fulcrumed to a casting 27 carried on a narrow 10 board 28 which extends across the galvanized steel bottom of the tub. This board also serves to support the guide 29 (Fig. 3) for the driving rack.

Pivottally connected to the lever 21 is a 15 connecting rod 30 which is in driving engagement with a crank on a large sprocket wheel 31. This sprocket wheel 31 is connected by means of a chain 32 to a smaller sprocket 33 mounted on one end of a counter- 20 shaft 34 on the outer end of which is a fly-wheel 35. When the machine is to be driven by a gasolene engine or electric motor, the fly-wheel 35 may be used as the belt wheel of the machine. The geared connection just 25 described, serves to increase the speed at the fly-wheel when the machine is worked by hand and serves to reduce the speed at the agitator when the machine is driven by power.

30 Sprocket 31 is mounted on one end of what may be designated the main drive shaft 36, this shaft being carried in a bearing 37 and carrying at its outer end the reversing mechanism for the wringer. The 35 reversing mechanism comprises a pair of bevel gears 38 and 39 loosely mounted on the main shaft 36 and permanently in mesh with a third bevel gear 40. A sliding clutch 41 with suitable ratchet faces can be moved 40 from its neutral and idle position, sidewise into engagement with ratchet faces on each of the bevel gears 38 and 39 so that the sprocket 42 carried by beveled gear 39 can be driven in either direction to drive the 45 chain 42' and the wringer roll connected thereto either forward or backward as desired.

The reversing mechanism for the wringer is disclosed more in detail and is claimed 50 in my co-pending application, Serial No. 664,589, filed December 7th, 1911. The mechanism whereby clutch 41 can be shifted, includes a rod 43 extending across the platform and equipped at its outer end with an 55 actuating bell crank 44 pivotally connected with a foot piece 45 and with a vertical rock shaft 46 in such a way that by pushing down on the foot piece or by turning the handle 47 of the rock shaft in its bearing plate 48, the wringer clutch will be slipped either way from its neutral position 60 to start the wringer either forward or reverse.

It will be understood that the wringer can 65 be out of gear when the agitator is in use or

both the wringing and agitating mechanisms can be in gear at the same time, if desired. The guide and catch 49 for the hand lever 26 of the agitator clutch 19 serves to keep that clutch in its proper place, either open 70 or closed, as desired.

When the machine is in operation and the agitator pins are whirling the clothes around within the tub, the centrifugal force throws the clothes toward the outside of the tub and raises the water at a higher level near 75 the top surface. Then when the agitator reverses in direction, the counter-current tends to cause the water to run over the top edge of the tub. To prevent overflow from this 80 source, an annular rim 50 is provided just at the top ends of the staves and extending entirely around the tub.

I claim:

1. In a washing machine, the combination 85 with a tub, of a tubular support detachably secured thereto and extending upwardly therein, a bushing freely mounted in each end of the support, a squared shaft connecting said bushings, a sleeve suspended over one of said bushings, upwardly extending pins carried by the sleeve, the upper end of said shaft resting within said sleeve to form a connection, means for operatively connecting the other of said bushings for driving 90 the sleeve alternately in opposite directions. 95

2. In a washing machine, the combination with a tub, of a support mounted within the tub, a sleeve encircling said support, the upper end of said sleeve being closed and 100 resting upon the support, a shaft extending through said support and connected directly to the closed portion of the sleeve, the said sleeve depending over the support and resting a short distance above the bottom of the 105 tub, a wooden block secured to the lower end of the sleeve, a plurality of pins mounted within the upper face of said block and means for driving the shaft whereby the sleeve will be oscillated for the purpose 110 specified.

3. In a washing machine, the combination with the tub, a tubular support detachably mounted within said tub, a squared shaft extending through said tubular support, a 115 sleeve mounted upon said tubular support and having a square socket for the reception of the upper end of the said squared shaft, pins detachably mounted in said sleeve extending upwardly and outwardly, and means 120 for driving said agitator alternately in opposite directions.

4. In a washing machine, the combination with the tub, an agitator support carried by the bottom of the tub, an agitator rotatably mounted on said support, an annular flange formed integral with the lower end of said agitator and extending adjacent the bottom of the tub, a wooden block detachably secured to said flange, a plurality of pins ex- 130

tending upwardly and outwardly adjacent to the top of the tub, and means for operating said agitator.

5. In a washing machine, the combination with the tub, of an internally threaded plate secured to the bottom of said tub, a tubular support detachably secured within said plate, bushings freely mounted within the opposite ends of said support, means for 10 connecting said bushings, an agitator supported upon said tubular support, means operatively connecting one of the said bushings with the agitator, and means operatively connecting the other said bushing for 15 driving said agitator alternately in opposite directions.

6. In a washing machine, the combination with the tub, an internally threaded plate rigidly secured to the bottom of the tub, a 20 tubular support detachably secured to said internally threaded plate and extending upwardly from the bottom of the tub, a bushing freely mounted within each end of said tubular support, a squared shaft extending 25 through said bushings and connected there-

with, a sleeve having a closed end, said closed end having a squared socket formed therein for the reception of the upper end of the squared shaft, the said sleeve being supported upon the bushing mounted within 30 the upper end of the support, an annular flange formed integral with the lower end of said sleeve and resting just above the bottom of the tub, an annular wooden block detachably secured upon said flange, a plurality of 35 pins detachably mounted within the upper face of said wooden block extending upwardly and outwardly, and means operatively connected to the bushing mounted within the lower end of said tubular support 40 for driving the said sleeve alternately in opposite directions for the purpose specified.

In witness whereof, I hereunto subscribe my name to this specification in the presence of two witnesses.
